UNITED STATES PATENT OFFICE

138,172

DESIGN FOR A ROTARY HEAD VENTILATOR FOR FLUES OR STACKS

Burt M. Lutze, Flint, Mich.

Application March 27, 1944, Serial No. 113,050

Term of patent 14 years

(Cl. D62—3)

To all whom it may concern:

Be it known that I, Burt M. Lutze, a citizen of the United States, residing at Flint, in the county of Genesee and State of Michigan, have invented a new, original, and ornamental design for a Rotary Head Ventilator for Flues or Stacks, of which the following is a specification, reference being had to the accompanying drawing, forming a part thereof.

Figure 1 is a side elevational view of a rotary head ventilator for flues or stacks, showing my new design;

Figure 2 is a front elevational view thereof;
Figure 3 is a top plan view thereof.

I claim:

The ornamental design for a rotary head ventilator for flues or stacks, as shown.

BURT M. LUTZE.
